UNITED STATES PATENT OFFICE.

OSCAR O. NYGAARD, OF SAUGUS, MASSACHUSETTS.

REFRACTORY-MATERIAL GRATE.

Application filed July 29, 1920. Serial No. 399,808.

To all whom it may concern:

Be it known that I, OSCAR O. NYGAARD, a citizen of the United States, and resident of Saugus, in the county of Middlesex 5 and State of Massachusetts, have invented an Improvement in Refractory-Material Grates, of which the following description, in connection with the accompanying drawings, is a specification, like letters on the drawings representing like parts.

My present invention is a fire grate brick, block, box or tuyère, intended and designed to take the place of iron grates, tuyères, and the like, particularly in the modern forms 15 of automatic stokers.

Heretofore it has been customary to employ fire brick of common form and various sizes, for the walls of furnaces, but I believe it to be a distinct novelty to devise 20 and provide a grate block, tuyère or the like of any form, made of refractory material such for example, carborundum and preferably molded, dried and burned in substantially the same manner as the manufacture 25 of fire brick, which refractory material shall be practically equivalent to and a substitute for the iron grates, tuyères and the like. I find that it is feasible and practical to form the usual fire clay or similar refractory material into suitable shapes to take 30 the place of the usual grate bars or tuyère plates and to burn these refractory tuyères or fire brick or plate articles, in a kiln, so that their surfaces will be vitrified and sufficiently hardened to withstand the frictional abrasion of fuel, such as burning coal, and also to so form my refractory fire brick with a plurality of air openings there-through, so that air under forced draft can 35 be supplied through such refractory material in a manner substantially identical with that now employed in iron grates and tuyère plates. The present excessive cost of iron, delays in securing it, difficulties in transportation and the like, have created considerable difficulties in the building and repairing of modern automatic stokers. My 40 invention, therefore, is of great importance in enabling such automatic stokers to be equipped with refractory tuyère plates, made at a locality adjacent the stoker at very slight expense. Furthermore, such refractory tuyère blocks can be quickly, easily and readily removed and renewed, with- 45 50 55

easy removal if desired, whereas an iron tuyère block, when warped, twisted or melted down, is frequently very difficult to extract from the stoker. These advantages 60 are of special importance at the present time and are of value in the further development and use of automatic stokers. It is well known in underfeed stoker practice that the height of the usual iron tuyères 65 covering the air channels between retorts is very limited. The maximum height measured at right angles to the edges on which the tuyères rest is considered to be five 70 inches from the lowermost tuyère opening to the uppermost opening.

This limitation is understood from the fact that the temperature in the middle and upper zones of the fuel bed in an underfeed stoker furnace is usually over 3000 degrees F. and the melting point of cast iron about 2200 degrees. 75

Although the air circulating through the tuyère helps keep it cool, it has been found insufficient to preserve the iron should the tuyère be extended higher into the fire bed, consequently the upper surface of an iron tuyère must be kept close enough to the retort to have the additional protection of the comparatively fresh fuel being fed from the 80 85 retort.

No such limitation is necessary in my refractory tuyère where the melting point is 4000 degrees F. and therefore capable of 90 withstanding the temperature in the fuel bed even without the protection of the air circulation,—and with such circulation making my refractory tuyère absolutely immune to the temperature in the fuel bed.

From this it will be understood that it 95 is practical with my refractory tuyère to have a height equal to twice that of any iron or metal tuyère, thereby greatly increasing the active burning surface of the furnace as well as, in corresponding degree, 100 the capacity of the furnace to burn fuel;—also, in comparison with an iron tuyère, greater efficiency for an equal quantity of coal to be burned per hour per retort; the static pressure in the air chamber beneath the tuyères will be greatly reduced due to the larger burning surface of my refractory tuyères as compared to that of iron tuyères, thereby reducing labor of the air supply 105 fan.

Another point of advantage in my refractory tuyère is that the expansive and 110

contractive action is many times less than that of iron or other metal and therefore the block will not crack and become useless. This advantage together with the great heat 5 resisting quality of my refractory tuyère insures a lasting fuel burning surface, eliminating costly shut downs for repairs, and effects a great saving of material and labor. However, my invention is not limited to the 10 tuyère blocks for automatic stokers, but can be employed as horizontal fire blocks, or grates, as will be further explained.

Referring to the attached drawings illustrating preferred embodiments of the invention, 15

Fig. 1 is a longitudinal section through the center line of a row of my refractory tuyères as assembled in an automatic underfeed stoker;

20 Fig. 2 is an enlarged perspective view of one form of tuyère block of refractory material;

Fig. 3 is a perspective view of the overfeed grate block;

25 Fig. 4 is an enlarged side view of a refractory grate block suitable for use in connection with retorts in automatic underfeed stokers;

30 Fig. 5 being a plan view and a cross sectional view through one row of tuyère openings;

Fig. 6 an enlarged longitudinal sectional view of the same; and

35 Fig. 7 is a fragmentary plan view of an underfeed stoker furnace showing the refractory tuyère blocks as applied to the retorts and the refractory grate blocks as applied to the overfeed portion of the furnace.

40 It will be appreciated that my invention contemplates and includes the formation of any desired type or form in contour of tuyère block. Fire clay or similar refractory material lends itself with peculiar adaptability to such conformation. By 45 having the surfaces of the refractory material on which the fuel rests and is moved, perforated with a considerable number of recesses, through which cool air under pressure is forced, these clay tuyère blocks are 50 kept remarkably cool and are thus automatically preserved. Furthermore the fuel supporting surfaces are fire resistant and the pressure of the air coming through the plurality of openings, maintains these openings 55 free of fuel, preserves and prevents the surface of the clay from being quickly burned out, prevents clinkers forming and acts equally with iron plates to stimulate combustion of the fuel in the retort. While I 60 have preferably illustrated the present invention as applied to the type of retort of the automatic stoker of my said prior application wherein a gravity feed is utilized in addition to the power pistons, the invention 65 is not limited to this type of stoker but

is herein shown for illustrative purposes only.

Referring to the drawing and as shown in Fig. 1, the usual type of retort is indicated at 1, a plurality of such retorts being arranged parallel and preferably at suitable angle, being supported upon iron girders or the like designated at 2 and the front wall, a fragment being shown at 3. A plurality of tuyère blocks designated at 5 70 5, 5, Fig. 1, are supplied, these tuyere blocks having usual fuel supporting surfaces 6 arranged substantially in the same inclination throughout as shown in Figs. 1 and 2, through which a plurality of perforations 75 7, 7, 7, 7, are formed. These tuyère blocks of refractory material, can be of substantially the same form and contour, as those now made of iron. Preferably, however, I make my refractory material of slightly greater 80 thickness to afford better wear resisting and longer life during burning. These tuyère blocks 5 may be of any dimensions for units and may carry the sides 8, 8, to rest upon the supporting retort surfaces as shown at 90 dotted line 9. A source of air under pressure, designated at 10, is supplied to force the air outwardly through the openings 7 in a manner similar to that employed in iron construction.

95 I prefer to form these tuyère blocks of refractory material with a plurality of strengthening floors or webs 12, which also will hold in any siftings which come through the openings 7 and thus prevent 100 choking up the air space underneath. The overfeed grate block 15 is clearly shown in Figs. 1 and 3, wherein a plurality of air openings 16, 16, 17, 17, are formed, preferably of different diameters. The overfeed 105 grate portions may be in suitable sections, preferably one for each retort and therefore arranged side by side for as many retorts as desired, these being supported on iron brackets or frames 18 or in any other suitable manner. Preferably I form this overfeed grate with a groove 24 adapted to fit over and interlock upon a member 19 carried by the bracket 18, but any other suitable means can be employed. I may also 110 form the dump grate 20 with a fire brick lining, coating or surface, the same being supported on metallic cross brackets 21, held by a crossbar 22 and adapted to swing upon a pivot 23.

115 In Figs 4, 5 and 6 I have illustrated in an enlarged and detailed form tuyère blocks of substantially the same type, but of a different contour from the one shown in Fig. 2. These tuyères 30 are formed with a forwardly extending rib 31 at either side, perforated at a plurality of points 32, 32, to receive the attaching bolts. The fuel supporting and fire resisting face 33 of this type 120 of tuyère is formed of substantial thickness 130

to insure long life and wear and with a plurality of air openings 35 therethrough. Reinforcing floors 37, 38 and 39 are fitted, which may be of iron to catch the siftings 5 and prevent choking the air supply chamber or channel beneath the tuyère, these plates being slidable and removable through grooves 40, 40, formed in the sides of the tuyère blocks. Siftings through the openings 10 35 can only take place at such time as the air supply to the air chamber or channel is shut off, when the movement of the fuel bed over the tuyères has a tendency to work the fuel into and through the openings and onto 15 the plates 39 which hold the siftings until the air is again admitted, thus forcing the siftings back into the fuel bed through the openings 35.

In Fig. 7 is illustrated a fragmentary 20 plan view of an underfeed stoker furnace of the type illustrated in Fig. 1 and showing the type of tuyère blocks illustrated in Fig. 2, such tuyère blocks being designated by the numeral 6 and showing therethrough 25 the perforations 7 extending into the interior of block. Also, this view shows clearly the arrangement and location of the floors 12 and also shows the retort sides 9 on which the tuyère blocks rest.

30 It will be readily appreciated that my idea of a fire brick for fire grate purposes, will afford a convenient, economical, easily obtainable and quickly renewable construction. Fire brick, particularly when supplied

35 with a substantial volume of air under pressure, resists disintegration to a high degree and such refractory material will, therefore, in many instances, outlast the iron grates, and tuyère blocks, now generally employed.

40 I believe that my conception of refractory material for this use and purpose, is new and important. I am well aware of the very general use of fire brick for furnace walls, side walls, back wall and front wall, as well

45 as roof, but I believe it to be a distinct novelty to endeavor to apply such or similar refractory material in a form and contour suitable for use as a fuel supporting grate and surface. It is this new use and feature,

50 together with the employment of such refractory material in connection with forced draft, which enables the same to be practicable, which I claim as new. Such re-

fractory material for tuyère blocks is especially new and useful in connection with 55 automatic stokers.

This invention enables the fuel or fire area of a furnace to be entirely lined with refractory material, the front, side and bridge walls being of fire brick and the fuel supporting surface being of my new refractory blocks. Thus the metallic surfaces are entirely protected and repairing these surfaces is greatly simplified and cheapened, while the life of the furnace or stoker, without repairs, is greatly increased. No allowance for uneven expansion and contraction of the iron and walls is needed, while the forced draft passing through the grates, 60 maintains the refractory material in its integrity. 70

My invention of a tuyère block having removable and renewable plates or floors is believed to be broadly new and applicable to tuyères of any kind of material, either 75 refractory, or of metal.

My invention is further described and defined in the form of claims as follows:

1. A tuyère block for automatic stokers, comprising an arched body portion having 80 its sides spaced apart and extending parallel to each other, the outer arched portion acting as a fuel supporting and fuel burning surface, and a plurality of floors arranged substantially horizontal and extending from the arched portion and between the parallelly arranged sides. 85

2. In a furnace having a plurality of retorts spaced apart to form air channels at the sides, the combination therewith of a 90 plurality of tuyère blocks spanning said air channels, each of said tuyère blocks comprising an arched body portion of refractory material having its sides spaced apart and extending parallel to each other, the outer arched portion acting as a fuel supporting and fuel burning surface, and a plurality of metallic floors parallelly arranged and extending from the inner side of said arched body portion into said air channels, and 95 said floors renewable separately from said arched body portion. 100

In testimony whereof, I have signed my name to this specification.

OSCAR O. NYGAARD.
